TAP GUIDE

Ralph E. Ashton, Arvada, Colo.

Application January 31, 1946, Serial No. 644,586

1 Claim. (Cl. 10—147)

1

This invention relates to mechanics' tools and facilities of hand or bench type, and more particularly to auxiliary means for selective association with conventional thread-cutting taps to guide and position the latter during use for improved quality and precision of results, and has as an object to provide an improved construction and cooperative arrangement of elements constituting such means.

A further object of the invention is to provide an improved guide for thread-cutting taps that is readily and conveniently adaptable to association and effective use with a wide range of specific tap sizes and lengths.

A further object of the invention is to provide an improved tap-guide susceptible of correlation with the shank sizes and lengths of conventionally standardized tap sets.

A further object of the invention is to provide an improved separable tap-guide construction whereby a single major element of the improvement is adapted to and for use with taps of differing shank sizes and lengths.

A further object of the invention is to provide an improved tap-guide having immediately interchangeable elements sized to receive and cooperate with taps of differing shank sizes and lengths.

A further object of the invention is to provide an improved separable tap-guide characterized by novel and efficient means for interengaging and frictionally holding the complementary elements of the device in operative relation with each other.

A further object of the invention is to provide an improved tap-guide that is simple and inexpensive of manufacture, sturdy and durable in construction, effective to accomplish the ends for which designed, and facile of use.

With the foregoing and other objects in view, my invention consists in the construction, arrangement, and combination of elements hereinafter set forth, pointed out in my claims, and illustrated by the accompanying drawing, in which—

Figure 1 is a vertical section taken axially through a typical embodiment of the invention as positioned in operative association with a conventional thread-cutting tap for practical use relative to a flat surface. Figure 2 is a section

2

similar to Figure 1 depicting an alternative arrangement and use of the invention. Figure 3 is a top plan view of the improved tap-guide major element freed from association with its operatively - essential complementary element. Figure 4 is a bottom plan view of the improved tap-guide major element. Figure 5 is a collective view embracing top plan representations of a plurality of typical complementary elements 10 interchangeably employable with the tap-guide major element. Figure 6 is a view similar to Figure 5 illustrating the elements of the latter showing in side elevation.

Internal screw-threading of cylindrical holes 15 in and through sections of rigid material is a common and recurrent operation incident to the construction, assembly, maintenance, and repair of a multitude of structures and devices. Except in the case of certain initial constructions, internal screw-threading is extensively accomplished by means of manually-actuated hand or bench tools known as taps, which, in a variety of types and specific constructions well standardized as to thread form, pitch and diameter, shank 20 diameter, and overall length, are normally included in the kits of well-equipped mechanics. Hand manipulation of conventional taps for the production of smooth, uniform screw threads in proper relation with the work stock is onerously difficult, particularly when the stock section to be threaded is thin, because of the necessity for maintaining the tap in axial coincidence with the hole being threaded while simultaneously rotating the tap about its axis; the manipulated 25 end of the tap remote from the work stock tending to wander through a more or less circular orbit or to incline away from the desired axial coincidence, with consequent thread deformation or mislocation, as the tap is rotated. To obviate 30 the difficulties and disadvantages above noted, and to facilitate the production of true, high quality threads by means of hand-actuated taps, the improved guide of the instant invention has been developed.

40 In the construction of the improvement as shown, the numeral 10 designates a straight, tubular member formed of any suitable hard, rigid material, such as metal, and with its axial bore opening through both of its ends. One end of the member 10 is worked or formed, in any con-

venient manner, to provide an integral, circumferentially-exterior flange 11 whereof the outer or free face is trued to a plane perpendicular to the member 10 axis, said flange 11 hence constituting a base or foot for the support of the member 10 on and in axially-perpendicular, upstanding relation with any flat surface. The member 10 is preferably relatively thick-walled, sized to a bore diameter such as will freely receive and accommodate a substantial range of tap sizes, and has a length sufficient to house the thread-cutting portion of work-engaged standard taps receivable therein, the shank and angular tool-receiving head of the tap projecting axially of and outwardly beyond said member when the flange 11 of the latter is in bearing relation against the work stock. The end of the member 10 remote from its flange 11 is reduced in exterior diameter to form an integral, thinner-walled extension 12 axially-coincident with and traversed by the member bore, which extension is adapted to telescopically cooperate with and removably and replaceably mount a tap-aligning cap in closing relation with said member end.

To accommodate differences in overall lengths of standard taps otherwise cooperable with a given member 10, the member end caps are of two distinct types, and to accommodate differing tap shank sizes, said caps, regardless of type, are provided in suitable number whereof each has a concentric, cylindrical bore sized to rotatably accommodate and serve as a guide bearing for a particular tap shank size. With the longer taps, typically represented at 13 in Figure 1, it is feasible and convenient to utilize a cap 14 having a relatively-thick base web, a cylindrical exterior surface conforming with that of the member 10, an annular marginal flange extending axially from the base web under surface to telescope snugly over and enclose the member end extension 12, and a concentric, cylindrical hole axially through the base web and of a size to fit smoothly about and rotatably accommodate a tap shank of particular size, such a cap completing the operative tap guide for association and use with a longer tap 13 in the manner clearly shown in Figure 1. Caps 14 may be provided for interchangeable use with a given member 10 in such number and assortment of base web hole sizes as may be feasible to operatively accommodate and guide the longer taps of any particular tap set or supply, the cap arranged to telescope exteriorly over the member 10 and being especially desirable in that its bearing for the shank end is thereby positioned at a maximum spacing from the work stock and hence for most efficient functioning as a guide in maintaining the tap in axial coincidence with the hole being worked. For use with shorter taps, represented at 15 in Figure 2, and where use of a cap 14 would not permit sufficient range of axial tap travel, a cap of the type indicated by the numeral 16 may be employed with the member 10 for functional effect the same as provided by the cap 14. The cap 16 is designed to telescope interiorly of the member 10 end extension 12 and to provide a guide bearing for a tap shank without unduly increasing the guide assembly length, for which purpose said cap 16 is formed with a relatively-thin base web adapted to overlie and engage against the end of the extension 12, a cylindrical, concentric boss projecting axially from its base web under side and of a diameter to telescope snugly within the extension 12, and a concentric, cylindrical

hole axially through said boss and of a size to fit smoothly about and rotatably accommodate a tap shank of particular size, said cap 16 hence serving to provide a guide bearing for the tap shank at the end of the member 10 remote from the work stock in essentially the same manner as the interchangeable cap 14, but in relatively diminished spacing from the member flange 11.

To minimize accidental separation of a selected cap 14 or 16 from mounted association with the member 10, while preserving facility of cap interchangeability, means are provided for automatically maintaining a resiliently-yieldable frictional grip between the extension 12 and the cap of either type associated therewith, said means conveniently taking the form of a slot or kerf 17 longitudinally intersecting and opening through the end of the said extension 12, and slightly skewed or twisted corners on said extension where said slot 17 intersects the extension outer end, one of said corners being twisted to outwardly overhang the extension outer wall, as indicated at 18 in Figure 3, in position to grip and frictionally hold interiorly of a cap 14 annular flange telescoped over the extension, and the other of said corners being twisted to inwardly overhang the extension inner wall, as indicated at 19 in Figure 3, in position to grip and frictionally hold exteriorly of a cap 16 cylindrical boss telescoped within said extension; said corners 18 and 19 readily springing under intentionally-applied pressures to permit removal and replacement of caps 14 and 16 relative to the member 10.

The improved guide assembly constructed and arranged as illustrated and described provides efficient means cooperable with a tap to hold said tap in the desired perpendicular relation with flat surfaced work stock 20, the flanged end surface of the assembly engaging solidly against the work surface to brace the guide and minimize tilting thereof as the guide assembly is held in position by one hand of an operator and the tap is rotatably manipulated by the operator's other hand. Since it is frequently necessary to thread holes intersecting arcuate work stock surfaces, typically represented by the showing of cylindrical stock 21 in Figure 2, it is convenient to form a V-shaped notch 22 diametrically across and in intersecting relation with the otherwise plane flange 11 free end, which notch serves in an obvious manner to seat the guide assembly relative to an arcuate work surface and to thereby brace said assembly to a considerable and helpful extent. End intersections of the notch 22 with the flange 11 take the form of V-shaped openings through which access may be had for the introduction of lubricants to the cutting elements of the tap and for the escape of chips from the member 10 interior.

Since many changes, modifications, and variations in the specific form, construction, and arrangement of the elements shown and described may be had without departing from the spirit of my invention, I wish to be understood as being limited solely by the scope of the appended claim, rather than by any details of the illustrative showing and foregoing description.

I claim as my invention:

In a tap guide having a rigid-walled, straight-bore, tubular member formed with a work-engageable foot on one end, means adapting said member for guiding cooperation with a tap shank, said means comprising a coaxial, reduced-diameter extension on the end of said member remote from said foot, a cap removably, replaceably and

telescopically engaging said extension, a relatively-thick end web in said cap disposed to close over the member bore, a bore for the rotatable accommodation of a tap shank through said end web coaxial with said member, a cut through and longitudinally of said member extension conditioning the cut-adjacent extension areas for limited yieldability radially of the member, and a skewed corner at the junction of said cut with the extension free end margin frictionally engaging the adjacent cap surface.
